DESIGN FOR A BROILER PAN

Martin C. Friedman, Grand Rapids, Mich., and
Irwin M. Stone, Cleveland Heights, Ohio

Application October 24, 1936, Serial No. 65,488

Term of patent 14 years

To all whom it may concern:

Be it known that we, Martin C. Friedman and Irwin M. Stone, citizens of the United States and residents respectively of Grand Rapids, Kent County, Michigan, and Cleveland Heights, Cuyahoga County, Ohio, have invented a new, original, and ornamental Design for a Broiler Pan, of which the following is a specification, reference being had to the accompanying drawing, forming a part thereof.

In said drawing, Fig. 1 is a top plan view of a broiler pan, showing our new design; Fig. 2 is a side view thereof; and Fig. 3 is a detail vertical sectional view on the line 3—3 of Fig. 1.

We claim:

The ornamental design for a broiler pan, as shown.

MARTIN C. FRIEDMAN.
